UNITED STATES PATENT OFFICE.

WILLIAM E. WHITE, OF MINNEAPOLIS, MINNESOTA.

JOIST-BAR SPACER.

1,366,230.

Specification of Letters Patent. Patented Jan. 18, 1921.

Application filed December 3, 1919. Serial No. 342,069.

To all whom it may concern:

Be it known that I, WILLIAM E. WHITE, a citizen of the United States, and resident of Minneapolis, in the county of Hennepin 5 and State of Minnesota, have invented certain new and useful Improvements in Joist-Bar Spacers, of which the following is a specification.

There is in general use in this country a 10 type of reinforced concrete floor construction known to the trade as combination tile and concrete slab construction. In such floor work rows of tile are placed end to end leaving a space between certain of the 15 rows. These spaces are filled with concrete containing suitable reinforcing bars. The tile on the opposite vertical sides and the form on the bottom or third side comprise the walls constituting the mold for the joist.

20 My invention relates to means for positioning and securely holding the reinforcing bars prior to and during the pouring of the concrete.

A supporting and spacing device designed 25 to meet these conditions must first provide a supporting feature to keep the rod or rods at the required distance from the form surface. This supporting element must in itself be elevated above the form in a manner permitting the free flow of concrete beneath it. 30 A second requirement is that a feature be included to correctly position the supporting member in relation to the long axis of the joist and preserve this position prior to and 35 during the concreting operation. In addition a feature is required to permit the ready fastening of the rods in the proper place on the supporting member.

The device I have invented to meet these 40 requirements is unique in that I make use of the fact that, as the tile rows are formed, blocks in consecutive rows take such relative position as to bring the open joints between adjoining tile substantially opposite, in relation to the space between tile 45 rows. Inasmuch as these joints or open spaces are from $\frac{1}{8}$ to $\frac{1}{4}$ of an inch in width, and inasmuch as the weight of the tile blocks is sufficient to cause them to remain 50 substantially in place as at first arranged, I provide as a means of support and alinement flat projections or wings formed integral with a supporting chair member and so disposed in relation to the chair member that 55 when in correct position, these wing mem-

bers fit in between the tile blocks on both sides of the space and effectively prevent displacement.

The invention will be more readily understood by reference to the accompanying 60 drawing, wherein,

Figure 1 is a perspective view showing the application of my invention to a typical floor construction.

Fig. 2 is an enlarged plan view of the 65 spacer; and

Fig. 3 is an elevation showing the means employed for securing a plurality of reinforcing bars on the spacer.

In the drawings floor tile are indicated at 70 1, 2, a space 3, remaining at the ends of adjacent tile, according to the usual practice. My improved spacer comprises a metallic strip of relatively light sheet metal having ends in the form of wings 4, and a 75 lateral flange 5, of a length substantially equal to the space provided between the rows of tile. The flange 5 is provided with spaced elongated apertures 6, and the vertical web 7 of the spacer is cut away at its 80 lower edge to provide an open space into which the concrete may be received as required in the use of devices of this sort.

As a fastening device for the reinforcing bars indicated at 10, I prefer to provide 85 spring wire clips composed of a bent portion 8, and re-bent points 9. These will be easily formed in a shape substantially the same as that shown in Fig. 3. In application they may be sprung over the bar and 90 snapped into the position shown, the bent ends 9, being deflected to permit the points to pass through the elongated openings 6.

Another important feature of my fastening means is that I do not require any tight 95 hold on the bar preventing free movement of the bar in the direction of its length. This allows ready adjustments in the position of the bar with reference to its length. I do effectively prevent its movement sidewise 100 or vertically in relation to my chair. I thus solve by extremely simple means all the requirements of the problem. I produce an article of marked economy as to material, simplicity of manufacture and of a form 105 very favorable for handling in large quantities, calculated to retain its first shape throughout all stages of handling in bulk. My manufacturing problem is simplified due to the simple nature of the dies required. 110

My labor problem is reduced to the extent that the placing of the fastening means requires neither strength nor skill.

A notable feature of my spacing device is in that it serves to locate and hold the bars against vertical and lateral movement and, so far as the spacing bar is concerned, is entirely embedded within the concrete. This result is secured by cutting at the web 7, the wings 4 having a bearing on the form beneath the tiles. The requisite strength, notwithstanding the cutting away of the web, is secured by forming the spacer of angular shape at that point.

15 I claim:

1. A joist bar spacer comprising in combination, a strip of metal bent to provide flat ends adapted to be accommodated in the spaces between the abutting ends of adjacent tiles and an intermediate portion having a vertical and a horizontal web, the horizontal web being apertured, and fastening clips having means adapted to coöperate with said apertures to secure a reinforcing bar to the spacer, substantially as described.

2. A joist bar spacer comprising in combination, a strip of metal bent to provide flat ends adapted to be accommodated in the space between the abutting ends of adjacent tiles and an intermediate portion having a vertical and a horizontal web, said web being of less height than said end portions, the

horizontal web being provided with elongated spaced apertures, and a spring fastening device having means adapted to coöperate with said apertures to secure a reinforcing bar, substantially as described.

3. A spacing device for concrete reinforcement comprising in combination, a strip of metal bent to provide flat vertically extending wings at its ends and a horizontal intermediate portion, said portion being apertured, and a fastening device having means adapted to coöperate with the apertures in said horizontal portion in order to secure a reinforcing bar thereto, substantially as described.

4. A joist bar spacer comprising in combination, a strip of metal bent to provide an intermediate portion of L-shape and end portions in the form of flat vertical wings adapted to be accommodated between the meeting faces of adjacent rows of tiles, the horizontal flange of the L-shaped intermediate portion being apertured, and fastening devices having means adapted to engage said apertures and to hold a reinforcing bar in position, substantially as described.

Signed at Saint Paul, Minn., this 26th day of November, 1919.

WILLIAM E. WHITE.
